UNITED STATES PATENT OFFICE.

JAMES MCENTEE, OF ROCHESTER, NEW YORK.

DIRECTION SIGNAL FOR MOTOR VEHICLES.

Application filed February 23, 1927. Serial No. 170,142.

The present invention relates to direction signals for motor vehicles and an object thereof is to provide a direction signal which may be mounted readily upon closed cars or vehicles without materially marring or disfiguring the vehicle. A further object of the invention is to provide for the mounting of a direction signal for operation between the upper edge of a sliding sash and the under side of the upper sill of a frame in which the sash slides.

To these and other ends, the invention consists of certain parts and combinations of parts, all of which will be hereinafter described; the novel features being pointed out in the appended claims.

In the drawings:

Fig. 1 is a fragmentary perspective view of a closed motor vehicle showing the direction signal mounted in position thereon, and in signaling position;

Fig. 2 is a plan view of the casing showing the signal member in dotted lines in its inner position;

Fig. 3 is a fragmentary plan view showing the signal member in its outer position;

Fig. 4 is a transverse section through the direction signal on the line 4—4, Fig. 3, the signal member being shown associated with the sash in its frame and being in signaling position;

Fig. 5 is a similar view showing a different manner of securing the casing of the direction signal to the frame, the signaling member being illustrated in the position that it occupies in moving to its inner position; and

Fig. 6 is a fragmentary front view with parts in section illustrating the form of the invention shown in Fig. 5.

Referring more particularly to the illustrated embodiment of the invention, 1 indicates a closed motor vehicle body having a door frame 2 with a sash 3 slidable in guides or grooves 4 formed in the frame.

Means is provided for forming a housing between the upper edge of the sash 3 and the under side of the upper sill 5 of the frame 2. This means, in this instance, consists in a single piece of sheet metal bent at 6 between its edges to provide an upper wall 7 and a lower wall 8 for a chamber 9, said chamber being closed at its inner edge by bend 6 and being open at its outer edge at the exterior of the car. Spacers 8^a hold the walls 7 and 8 in spaced relation. The upper wall 7 may

have a flange 10 projecting upwardly from its outer edge to form a facing strip for the outer face of the upper sill 5. The manner of securing this housing or casing in position is immaterial. In one instance, as shown in Fig. 4, screws 11 may be passed through the casing and into the upper sill 5 through the lower surface thereof while, in the other instance, as shown in Figs. 5 and 6 the upper sill may have a removable strip 12 secured thereto by screws 13 and this strip may engage with angular projections 14 extended upwardly from the upper wall 7 and held between the strip 12 and the sill 5.

The signal member, in this instance, is in the form of an arrow 15 which is mounted to turn on one arm 16 of a lever pivoted at 17 within the housing or casing. The axis about which the arrow turns on the lever extends transversely of the axis of turning of the lever but longitudinally of the arrow. In order to limit the movement of the arrow 15 on the lever arm 16 and at the same time to hold the arrow to the arm, the arrow is provided with a slot 18 which exposes the arm and a screw 19 which passes through said slot and is anchored in the arm 16 thus holding the signal member 15 against longitudinal movement on the arm 16 and at the same time limiting the turning movement on the arm. A spring 20 surrounds the swinging arm 16 and has one end anchored at 21 to the signal member and its other end 22 cooperating with the top wall 7 of the casing. This spring acts on the signal arm 15 in such a manner that said signal member has a normal tendency to lie with its flat faces vertically arranged. The other arm 23 of the lever extends through a slot 24 in the inner wall 6 of the housing and it is provided at its free end with a handle 25 through which the lever may be swung on its pivot 17 to cause the signal member 16 to move from the housing to signaling positions or into the housing to nonsignaling position.

Assume that the signaling member lies within the housing in nonsignaling position as shown in Fig. 2 and it is desired to move the same to signaling position as shown in Fig. 1, the user of the device grasps the handle 25 and pushes forward on the same, swinging the lever on its pivot 17. As the signaling member moves out of the housing, it turns on the arm 16 of the lever under the action of the spring 20 until it assumes a

vertical position. The movement of the lever is continued until the spring 20 passes behind the abutment or projection 26 formed on the top wall of the housing to hold the signal member in its outer position.

When it is desired to move the signal member within the housing to nonsignaling position, the user pulls rearwardly on the handle 25 which causes the lever to move on its axis 17 and brings the rear edge 27 of the signal member 15 below the arm 16 in engagement with the lower wall 8 of the housing, thus causing the signal member 15 to turn on the arm 16 and reenter the housing 13 to the position shown in Fig. 2.

From the foregoing it will be seen that there has been provided a direction signal which is adapted to be positioned upon a closed vehicle in such a manner that the disfiguring of the vehicle does not occur. The indicator is mounted to turn on a swinging lever so that it may enter sidewise into a housing adapted to be positioned between the upper edge of a sliding sash and the under side of the upper sill of the frame in which the sash slides. A spring is interposed between the lever and the indicating member which, as the indicating member moves from the housing or casing, causes the indicating member to turn from a horizontal position to a vertical position on the lever. The construction is simple in operation, inexpensive to manufacture and durable in use.

It will be noted that the housing is comparatively thin and so situated that when the direction indicator is enclosed therein, the device as a whole is practically invisible.

What I claim as my invention and desire to secure by Letters Patent is:

1. The combination with a frame having a sash opening and a sash slidable in the frame, of means fixed relatively to the frame and in the sash opening between the upper edge of the sash and the lower face of the upper sill of the frame, said means being coextensive in length with the width of the sash opening and provided with a chamber, and a direction indicating member mounted to move into said chamber to an inoperative position and from said chamber to a signaling position.

2. The combination with a frame having a sash opening and a sash slidable in the frame, of means fixed relatively to the frame and in the sash opening between the upper edge of the sash and the lower face of the upper sill of the frame, said means coextensive in length with the width of the sash

opening and provided with a chamber, of a lever mounted to swing in said chamber about an upright axis and having an operating portion lying on the inner side of the frame, and a direction indicating member mounted to turn on a horizontal axis on said lever so as to move into and out of the chamber.

3. The combination with an elongated housing having two parallel walls and a connecting wall at one side forming a chamber opening at the side opposite the connecting wall, of a lever mounted to swing about a vertical axis in said chamber nearer one end of the housing than the other and having an operating portion extending through the connecting wall, and a direction indicating member mounted to turn on the lever about a horizontal axis.

4. The combination with an elongated housing having two parallel walls and a connecting wall at one side forming a chamber opening at the side opposite the connecting wall, of a lever mounted to swing about a vertical axis in said chamber and having an operating portion extending through the connecting wall, and a direction indicating member mounted to turn on the lever about a horizontal axis, said direction indicating member having a portion for cooperating with a portion of the housing to cause the direction indicating member to swing on the lever about the horizontal axis in order to enter the housing, and a spring also acting on said direction indicating member to cause the latter to swing on the lever as the direction indicating member is moved by the lever from the housing.

5. The combination with a housing having an upper and lower horizontal wall spaced apart and an inner connecting wall, said inner connecting wall having an opening, a lever pivoted between the upper and the lower wall and having a portion projecting through said opening in the connecting wall, a direction indicating member mounted to swing on the lever about a horizontal axis, said lever having a portion at its inner end arranged to cooperate with the bottom wall of the housing to cause the indicating member to swing on the lever as the indicating member is moved into the housing, and a spring surrounding a lever and connected with the indicating member to cause the indicating member to turn on the lever as the indicating member is moved from the housing.

JAMES McENTEE.
